United States Patent

Des. 241,703
Patented Oct. 5, 1976

241,703

FOOD STORAGE CONTAINER

Harold P. Ashton, Providence, R.I., assignor to
Dart Industries Inc., Los Angeles, Calif.

Filed Mar. 21, 1975, Ser. No. 560,467

Term of patent 14 years

Int. Cl. D7—06

U.S. Cl. D7—76

FIG.1

FIG.2

FIG.3

FIG.4

FIG.5

FIG.6

FIG. 1 is a top perspective view of a food storage container showing my new design;

FIG. 2 is a top exploded perspective view thereof;

FIG. 3 is a top plan view of the closure;

FIG. 4 is a top plan view of the container;

FIG. 5 is a front exploded elevational view thereof;
and

FIG. 6 is a bottom plan view thereof.

I claim:

The ornamental design for a food storage container, substantially as shown.
